UNITED STATES PATENT OFFICE.

JEREMIAH M. CURRIER, OF LOUISVILLE, KENTUCKY, ASSIGNOR OF ONE-THIRD TO CLARENCE SALE, OF LOUISVILLE, KENTUCKY.

COMBINED SAD-IRON AND VAPOR-STOVE.

SPECIFICATION forming part of Letters Patent No. 700,180, dated May 20, 1902.

Application filed June 7, 1901. Serial No. 63,575. (No model.)

To all whom it may concern:

Be it known that I, JEREMIAH M. CURRIER, a citizen of the United States, residing at and whose post-office address is No. 148 West 5 Main street, Louisville, in the county of Jefferson and State of Kentucky, have invented new and useful Improvements in a Combined Sad-Iron and Vapor-Stove, of which the following is a specification.

10 This invention relates to combined sad-irons and vapor-stoves, and more particularly to that class in which a gasolene or other hydrocarbon vapor-burner is employed for supplying the necessary degree of heat to the 15 bottom of the base of the device during the operation of ironing or upwardly for heating the top plate or for cooking purposes when the top plate is removed.

The primary object of the invention is to 20 provide a detachable heating device for the combined sad-iron and vapor-stove which may be interchangeable to any base of the same make, so that it will not be necessary to supply or provide a separate heating device for each independent base.

A further object is to provide a cheap, durable, and efficient heating mechanism which may be readily detached and its parts separated for cleaning or for other purposes.

30 Other objects of the invention, as well as the peculiar construction thereof, will be fully described hereinafter and illustrated in the accompanying drawings, in which—

Figure 1 is a perspective view of a combined sad-iron and vapor-stove constructed in accordance with my invention and arranged for ironing. Fig. 2 is a top plan view of the combined sad-iron and vapor-stove arranged for cooking purposes, the handle and 40 top plate, as well as the oil-receiving reservoir, being omitted. Fig. 3 is a vertical longitudinal sectional view through the combined sad-iron and vapor-stove arranged for ironing. Fig. 4 is a perspective view of the 45 heating mechanism detached, the burner being arranged for directing the flame upwardly.

Referring now to the drawings by numerals of reference, 1 designates the base of the device, which is hollow, being provided with

side walls 2 and 3, the upper edges of which are corrugated or fluted, as shown at 4 and 5. The rear end of the base is provided with an extension 6, having a flange 6^a, a transverse rib 7 being formed at the juncture of the flange with the base to provide with the rib and extension an initial-heating cup 7^a. This rib 7 projects a slight distance from the bottom of the base beneath the rectangular block 8, which carries the heating mechanism. 55 This block is of sufficient width to fill up the space between the inturned edges 9 and 10 of the side walls 2 and 3 and is securely held in place by its vertically-extending flanges 11 and its bottom flange 12 on the inner side of 60 the inturned edges and by an overlapping plate 13, which engages the opposite sides of the inturned edges of the walls 2 and 3, so as to form grooves 8^a, in which said inturned edges are seated. Running longitudinally of 65 the base and through the groove 14 in front thereof is a supply-pipe 15, to one end of which is secured the oil-reservoir 16, adapted to contain gasolene or other hydrocarbon. The other end of said pipe passes through the 70 block 8 and communicates with an angular valve-casing 17 through the overlapping plate, which is formed on and is secured with the latter to the block 8, the height of the 75 overlapping plate being approximately the same as the diameter of the upper horizontal arm of the valve-casing and its width. (Indicated by dotted lines in Fig. 3.)

18 is a needle-valve seated in the valve-casing and normally closing the outlet-port 19, 80 which is arranged adjacent to and spaced a short distance from the burner. This burner comprises an inner cylinder 20, open at its rear end and having rows of perforations along the side through which the fuel is admitted in the form of vapor ready to be ignited. This cylinder snugly fits and is adapted to be turned in and is supported by a bifurcated casing 21, secured to the block 8 and provided with a longitudinal slot 22 at 85 its upper side coinciding with the perforations in said cylinder when in their upper position. A lever or pin 23 projects from the cylinder through an elongated slot 24 in the casing, and by turning said cylinder one- 90 95 100

fourth of a revolution from its normal position by means of the lever or pin the flame may be readily extinguished.

A diametrically oppositely disposed longitudinal lower slot 22^a is arranged in the casting 21, the purpose of which is to permit the ignited gas to come in direct contact with the base, and thus cause the same to heat the bottom of the base when the cylinder is turned one-half a revolution from its normal position to bring the perforations into their lower position. When the flame is admitted through the upper slot 22, the device can be used as a vapor-stove or heater.

15 25 designates transverse grooves in the top edge of the base 1 and which are located on a parallel plane with the top edges of the corrugations 4 and 5 of the side walls 2 and 3. The inturned edges 9 and 10 of the walls 2 and 3 are provided with shoulders 26 on which rest a top plate 27, the front edge of which engages the grooves 25. Screws 28 and 29 pass through the inturned edges of the side walls and engage the rear of the plate 27 to securely 25 lock it in place. The handle 30 and guard-plate 31 are carried by the plate 27, and to remove the plate, and incidentally the handle and guard, it is only necessary to release the screws 28 and 29, so as to withdraw them 30 from contact with the plate.

By the peculiar construction of the block 8 and the arrangement of the plate 13 it will be readily apparent that the entire mechanism for heating the combined sad-iron and 35 vapor-stove can be readily removed by simply taking off the plate 27. When the plate 27 is secured in place, it will seat at its rear end over the block and will incidentally retain the heating mechanism in place. However, the removal of the plate 27 will not necessarily necessitate the removal of the heating mechanism, as it may be found convenient or desirable to utilize this device as a 40 stove for heating liquids and for other purposes. In this event the plate will be removed 45

and the article to be heated will be placed upon the corrugated edges of the side walls of the base and the vapor in the burner ignited substantially in the same manner as when the device is used for laundering purposes.

From the foregoing it will be readily apparent that by utilizing a construction of combined sad-iron and vapor-stove in its coöperating parts similar to the one illustrated and described by me no inconvenience will be experienced in removing the heating mechanism for any purpose and that I have provided a cheap, durable, and efficient device of the character described which will readily meet the requirements of the trade.

Having thus fully described my invention, the following is what I claim as new therein and desire to secure by Letters Patent:

1. A combined sad-iron and vapor-stove, comprising a base, and a burner secured to the base and consisting of an outer bifurcated casing having longitudinal upper and lower slots, and an inner cylinder having rows of perforations and rotatable and fitting snugly within the bifurcated casing so as to expose the rows of perforations to either of the longitudinal slots.

2. A combined sad-iron and vapor-stove, comprising a base, and a burner secured to the base and consisting of an outer bifurcated casing having longitudinal upper and lower slots, and a transverse slot, and an inner cylinder, having rows of perforations and a lever working in the transverse slot, whereby the inner cylinder is adapted to be rotated so as to expose the rows of perforations to either of the longitudinal slots.

In testimony whereof I affix my signature in presence of witnesses.

JEREMIAH M. CURRIER.
